WILLIAM TIVENDALE, OF CLYDEBANK, SCOTLAND, ASSIGNOR TO THE SINGER MANUFACTURING COMPANY, A CORPORATION OF NEW JERSEY.

MACHINE FOR STRAIGHTENING LIGHT BARS, NEEDLES, AND THE LIKE.

1,164,683.

Specification of Letters Patent. Patented Dec. 21, 1915.

Application filed June 2, 1911. Serial No. 630,955.

To all whom it may concern:

Be it known that I, WILLIAM TIVENDALE, a subject of the King of the United Kingdom of Great Britain and Ireland, and residing at Clydebank, Dumbartonshire, Scotland, have invented certain new and useful Improvements in Machines for Straightening Light Bars, Needles, and the like, of which the following is a specification, reference being had therein to the accompanying drawings.

This invention has for its object to provide a simple and effective mechanism for straightening light bars or wires, and particularly sewing machine needles, and the following description relates more particularly to the truing of sewing machine needles subsequent to the tempering operation. It is embodied in a machine preferably constructed with a reciprocatory needle-inserter in the form of a hopper having its delivery end portion movable into and out of alignment with the jaws of a needle-shank gripping chuck or movable support mounted for rotation upon a longitudinally traveling carriage and provided with periodically acting means for opening and closing the chuck-jaws to release a straightened needle and to grasp a succeeding unstraightened needle delivered thereto by the hopper. Under the preferred action of its feeding mechanism the carriage advances to bring the part of the needle-blade adjacent the shank into the range of action of a straightener in the form of a reciprocating hammer and above an adjacent anvil or stationary needle-support, the needle preferably entering between the spaced jaws of a feeler close to and preferably upon the opposite side of the anvil from the path of the hammer. As the carriage performs its retractive feeding movement, during which preferably uniform rotation is imparted to the chuck, the hammer strikes the needle-blade a succession of blows in preferably concentrated groups or series adjacent the shank and eye, respectively, and an extended intermediate series along the blade during such rotation, the impact of the hammer being controlled by an impact-regulator comprising a wedge-block connected with said feeler and affording a movable stop to vary the blow of the hammer at the instant of delivery and cor-

respondingly with the degree of deflection or eccentricity of the needle. The hammer is arranged to move in a path close to the anvil and between the same and the needle-holding chuck, while the feeler, which is governed in its action by the deflection of the needle from its axis of rotation, is also preferably arranged close to but upon the opposite side of the anvil, which latter is preferably rounded upon the side toward the hammer path, so that the edge of the anvil, adjusted so as to present its operative face slightly below the blade of a straightened needle mounted in the chuck, is close to the feeler.

It has been found in practice in the tempering of needles that the distortion due to successive heating and rapid cooling is greatest at the points where differences in thickness occur, viz., at the junction of the blade with the shank and at the eye, while in the intermediate portion the distortion is comparatively slight. Owing to the small amount of deflection of needles having even the maximum degree of distortion received under actual working conditions, and the extremely small power possessed by the needles to actuate the impact regulator, the effective action of the hammer can be automatically controlled only within a comparatively limited range of adjustment. Furthermore, it has been found impracticable, without materially increasing the complexity of the mechanism, to time the hammer-blows so that they shall be delivered invariably in exact register with the extreme point of deflection of the needle. Accordingly, instead of adjusting the machine to deliver one or more straightening blows in exact register with the bend or crook to be removed, at or intermediate the extremities of the blade during the rotation of the needle, the mechanism is constructed to produce in each cycle a comparatively large number of relatively light blows in quick succession, the period of action of the hammer and the lengthwise feed of the needle being so timed that a primary series of regulated blows is delivered upon the blade adjacent the shank while the needle continues to rotate, so that a sufficient number of impacts is delivered in such portion of the needle to perform the

straightening action cumulatively. A further series of blows is distributed along and around the blade in such manner as to remove any deflection therein intermediate the shank and a point near the eye, at which point the feed of the needle is again arrested for delivery of a final series of concentrated regulated blows around the circumference of the needle-blade adjacent the eye, preferably somewhat greater in number than the primary series of blows, with an effect at such point similar to that previously produced adjacent the shank.

The present invention consists primarily in the special arrangement of the anvil, the hammer and the needle-holding and the feeding means whereby the needles are automatically straightened successfully, which result has been found impracticable of attainment heretofore, notwithstanding the wide range of experimental work which has been performed with this end in view.

The invention further consists in the special relation to the hammer and the anvil of the feeler which engages the needle-blade upon the opposite side of the anvil from the path of the hammer, and in various special constructive features of the machine.

In the accompanying drawings, Figure 1 is a side elevation of a machine embodying the present improvements, with the bed and other portions partly in section, Fig. 2 a plan of the same, Fig. 3 a transverse sectional elevation of the chuck-carriage-supporting end portion of the machine, and Fig. 4 a partial transverse sectional view of the machine taken intermediate the ends. Fig. 5 is a detached perspective view showing the hammer-head, the anvil, the feeler-arm embracing the needle-blade and a portion of the impact-regulating mechanism connected therewith. Fig. 6 is an enlarged perspective view partly in section, showing the wedge-block of the impact-regulator and the parts of the hammer mechanism with which it operates, and Fig. 6^a a side elevation of the wedge-block detached. Fig. 7 is a perspective view of a portion of the needle-tray-shifting mechanism. Figs. 8 and 9 are perspective views representing portions of the device for periodically arresting the rotation of the chuck-spindle. Fig. 10 is an enlarged sectional plan of the needle-chuck. Fig. 11 shows the hammer nose-piece with a transverse notch having convergent sides to insure the centering of the needle-blade beneath the hammer. Figs. 12 and 13 represent developments of the hammer throw-out and feed-cams, respectively.

60 The machine is shown provided with the flat base 1 to which are bolted the feet of the end standards 2 of the bed 3 of the frame, one of the standards 2 being provided with bearings 4 in which is journaled the transverse main or driving-shaft 5 carry-

ing the loose belt-wheel 6 having a hub 7 whose inner end is formed with a radial notch entered by a tongue 8 of the collar 9 fixed upon the shaft by means of the pin 10. The outer portion of the pulley hub 6 is 79 formed with an annular groove 11 entered by inwardly extending pins 12 of the yoke 13 of a lever 14 whose hub is adjustably secured by means of the nuts 15 and 16 upon a reciprocating rod 17 slidably mounted in 75 the bearing bosses 18 of the standard 2 and provided at the forward end with a knob 19. The threaded outer end of the shaft 5 is provided with a split internally threaded 80 thrust-collar 20 between which and the adjacent end of the pulley-wheel hub 7 is interposed the spring 21 for normally maintaining the notch of the pulley-wheel hub in operative engagement with the tongue 8 of the fixed collar 9. Fulcrumed upon a 85 screw-stud 22 tapped into the forward bearing boss 18 is a latch-lever 23 having at one end an offset finger-piece 24 with its opposite end normally in engagement with a block 25 fixed upon and affording a detaining shoulder of the reciprocating clutch-rod 17, the operative end of the lever 23 being drawn downwardly to rest in engagement with the block 25 by means of the spring 26. In the normal operation of the machine, 90 when the pulley-wheel 6 is clutched to the main-shaft 5 under the action of the spring 21, the block 25 of the rod 17 lies beneath the operative end of the latch-lever 23, but to stop the rotation of the main-shaft the knob 19 is pushed by the operator to disengage the tongue 8 from its notch in the pulley hub 7, and the operating rod 17 is held retracted by the snapping of the end of the latch-lever behind the block 25, the parts 100 being thus maintained until the finger-piece 24 of the latch-lever is depressed by the operator, when the operating rod 17 is released and the pulley-wheel is again clutched to the main-shaft. The tongue 8 of the 110 fixed collar 9 is made of taper form so as to oppose an inclined shoulder to the adjacent wall of the radial groove in the pulley hub 7 for forcing the pulley 6 backwardly 115 in opposition to its spring 21 in case an abnormal resistance should be placed upon the main-shaft 5 by the jamming of certain parts connected therewith.

The top of the bed 3 affords a seat for the base-plate 27 of the sliding chuck-carriage 120 which is confined in a guideway thereon with the overhanging guide-bars 28 secured in position by screws 29 and entering side-grooves in the base-plate 27, the lower portion of which is maintained in suitable 125 alignment by means of wearing strips 30 interposed between the same and the sides of the guideway and laterally adjustable by means of the screws 31 with jam-nuts 32. The base-plate 27 has a depending boss 33 130

entering an aperture 34 in the bed 3 and is provided with a stud 35 carrying a roller 36 entering a groove or pathway 37 of the feed-cam-cylinder 38 which is fixed upon the cam-shaft 39 mounted in depending bearings 40 of the bed 3. The cam-shaft carries near its rearward end the worm-wheel 41 meshing with a worm 42 fixed upon the transverse driving shaft 5 from which connection the cam-shaft derives its operative rotary movements at a relatively slower speed than that of the driving shaft.

The bed-plate 27 of the carriage is provided with two upright bearing members 43 provided with the aligned bushings 44 formed with reversely tapered apertures, and within the forward bushing is fitted the correspondingly tapered journal 45 of the tubular chuck-spindle 46 having slidingly secured by means of a spline 47 near its opposite end the conical collar 48 externally fitted to the bore of the rearward bushing 44 and held in contact therewith by means of the internally threaded split collar 49 applied to the threaded extremity of the chuck-spindle 46 and clamped thereon against turning by means of the clamp-bolt 50. The spindle 46 is formed at the forward end with the cylindrical head 51 formed with transverse slots 52 in which are pivoted by means of the pins 53 the levers 54 formed at their forward ends with the opposed needle-gripping jaws 55 fitted, in a manner well known, to the needle shanks n' whose blades n are to be straightened. The levers 54 are slotted longitudinally near the inner edges to form yielding tongues 56 engaged by the points of adjusting screws 57 secured in position by the lock nuts 58, whereby the space between the rounded extremities 56^x of the tongues 56 may be adjusted to compensate for wear. The chuck-head 51 has secured thereto by means of the screws 59 the feet 60 of spring-blades 61 entering the slots 52 and resting upon the outer edges of the clutch-levers 54 for normally pressing them inward to separate the chuck-jaws 55.

Fitted slidingly within the hollow chuck-spindle 46 is the reciprocating rod 62 having its forward portion flattened at 63 and wedge-shaped at its extremity 64 to enter the space between the rounded ends 56^x of the chuck-lever tongues 56, the rod 62 having a lateral groove 65 entered by the reduced inner end of a transverse screw 66 in the chuck-spindle by means of which the rod 62 is connected to rotate with the chuck-spindle but adapted to move endwise therein. The rearward end of the chuck-operating rod 62 has secured thereon by means of the pin 67 the hub 68 of a collar 69 provided with an annular groove 70 entered by inwardly extending pins 71 of a fork 72 in the upwardly extending arm 73 of a rock-

lever fulcrumed by means of the pin 74 upon the bracket 75 carried by the chuck-carriage bed-plate 27, said rock-lever having a depending arm 76 carrying a roller-stud 77 entering a groove or path-way 78 of a cam-cylinder 79 also fixed upon the cam-shaft 39. As shown in the drawings, the cam-cylinder 79 presents a smooth cylindrical surface beneath the roller-stud 77 during the travel of the chuck-carriage under the action of the cam 38, and its cam-plates 78^x are so arranged and proportioned that they operate upon the rock-lever only during the period when the chuck is to be opened and closed, and while the carriage is temporarily at rest in retracted position.

The chuck-spindle 46 has fixed thereon the conical bushing 80 and is provided with a sleeve 81 slidingly fitted thereto and locked from turning thereon by means of a spline, 85 said sleeve carrying a second bushing 82 with conical outer face oppositely directed to the fixed bushing 80; and upon these bushings is fitted the conically recessed hub 83 of a grooved belt-wheel 84. To the externally threaded portion of the chuck-spindle 46 adjacent the sleeve 81 is applied an internally threaded thrust-collar 85, between which and the sliding bushing 82 is interposed the spring 86 by means of which the pulley 84 for rotating the needle-chuck has a frictional driving connection with the chuck-spindle.

The needle-inserter is shown as a hopper constructed with the parallel plates 87 and 88 separated apart slightly more than the thickness of the needle-shanks by means of the lateral strip 89, and secured together by means of the screws 90. Secured upon the plate 87 by means of screws 91 is a plate 92 formed with a lip 93 adapted to afford one side-wall of the channel-way for the needles of which the other wall is formed by the inner edge of the spacing strip 89. Secured to the outer faces of the lower portion of the needle-hopper by means of screws 94 are the shanks 95 of spring-needle-holders having inwardly recessed jaws 96 adapted to embrace the lower needle-shanks as they gravitate downwardly through the hopper, 115 one pair of said jaws entering the apertures 55^x formed therefor in the chuck-jaws and the other extending just in front of the chuck-jaws when the hopper is in operative or needle delivering position, as represented 120 in the drawings.

To the back of the needle-hopper is secured one member of an angle-piece 97 whose other member is adjustably secured by means of the screw 98 to the forward extremity of a supporting arm 99 having its hub 100 adjustably secured by means of the set-screw 101 upon a rock-shaft 102 journaled in suitable bearings 103 of the brackets 104 secured to the bed 3 by means of screws 130

104*. The hub 100 of the needle-hopper supporting arm has an upwardly extending arm 105 in which is swiveled a pin 106 having pivotally connected to its head 107 by means of the transverse pin 108 the rearward end of a pressure-lever 109 whose forward end passes through a transverse slot 110 in the needle-hopper and rests upon the shank of the top needle therein, the requisite pressure being imparted to the lever 109 by means of a cord 111 extending downwardly through an aperture 112 in the bed 3 and in practice carrying a weight.

The rock-shaft 102 has loosely mounted thereon the laterally extending lever 113 connected by means of the pivotal pin 114 with the upper end of a link 115 extending downwardly through an aperture in the bed 3 and having its opposite end connected by means of the pin 116 with one end of a lever 117 extending crosswise and above the cam-shaft 39 and having its opposite end supported by means of a pivotal pin 118 in the bearing bracket 119 secured by means of screws 120 to the under side of the bed 3. The lever 117 carries a lateral stud 121 normally resting upon the periphery of a cylindrical cam-ring 122 fixed upon the cam-shaft 39 and provided at one point in its periphery with a notch or recess 123. The pivotal pin 114 projects through and beyond the link 115 and its reduced outer portion affords a support for the lower side of a rigid arm 124 preferably notched to receive the same and having a hub 125 fixed upon the rock-shaft 102 by means of the transverse pin 126. As the pin 114 affords a support for the arm 124 of the shaft 102 carrying the needle-hopper, and the position of the pin 114 is determined by that of the lever 117, it will be observed that when the stud 121 is upon the periphery of the cam-ring 122 and the link 115 and supporting pin 114 are in elevated normal position, the needle-hopper will be in upper retracted position entirely out of the range of movement of the chuck, which is permitted to rotate freely and to travel with its supporting carriage in feeding the needle toward and from straightening position; but when the stud 121 of the lever 117 enters the notch 123 of the cam 122, and the lever 117 drops, the needle-hopper will be lowered into operative position to present a needle embraced by its spring-jaws 96 to the chuck-jaws 55. The rock-shaft 102 has secured thereon by means of the set-screw 127 the hub 128 of a depending arm 129 having a laterally offset portion 130 adapted to engage the adjacent bearing bracket 104 when the needle-hopper is manually raised into substantially horizontal position for renewal of the supply of needles or for other purposes.

Secured upon the bed 3 by means of the screws 131 is the anvil-supporting block 132

having an extension 133 upon the top affording a vertical seat 134 to which is secured the anvil 135 in the form of a flat plate whose upper edge 136, beveled or rounded on the side adjacent the chuck-carriage, affords a support upon which the needles are bent in the straightening operation. The anvil-plate has a transverse slot 137 parallel with its operative edge which is entered by the clamp-screws 138 passing through a cap-plate 139 by means of which the anvil is secured in position. The top of the body portion of the anvil block 132 is provided with a vertical slot with the bottom slightly inclined to afford a bearing for the wedge-plate 140 having a similarly inclined lower edge, and with its upper edge affording a seat for the lower edge of the anvil-plate. The wedge-plate 140 has a T-head 141 through which are tapped the adjusting push-screws 142 with points resting against the end of the anvil-block 132, and is provided with an aperture 143 entered by the adjusting screw 144 which is tapped into the anvil-block 132 intermediate the push-screws 142. The operative edge 136 of the anvil is set normally below the axis of rotation of the needle-chuck a distance slightly greater than one-half the diameter of the needle-blades, but its height is made adjustable to vary this distance as may be required and to compensate for wear, by adjusting the position of the wedge-plate 140 transversely to the chuck-spindle. This is accomplished by manipulation of the adjusting screws 142 and 144 in a manner well known.

The hammer comprises the wedge-shaped nose-piece 145 whose reduced operative end is shown formed with a transverse groove or notch 146 to receive and center the needle-blade, the nose-piece being provided with the threaded shank 147 adapted to be secured in the correspondingly threaded socket of the hammer-head 148 which is provided with the usual transverse eye to receive the helve 149 upon which it is adjustably secured by means of the set-screw 150. The helve 149 is in the form of a vibratory arm having a hub 151 adjustably secured by the set-screw 152 upon the hammer-supporting rock-shaft 153 journaled in suitable bearings 154 of the bracket member 155 secured by bolts 156 upon and at one end of the bed 3. To the lower side of the helve adjacent the hub 151 is secured by means of screws 157 the wearing plate 158 normally resting upon the periphery of the cam-wheel or trip 159 which is provided with a series of high-points or teeth 160 and low points or notches 161 whose engagement with the outer end portion of the wearing plate 158 causes the alternate lifting and release of the helve 149 for imparting operative movements to the hammer-head, whose path of movement is ad-

ja⁵cent the operative edge 136 of the anvil and relatively remote from the chuck-jaws 55 between which and the anvil it has its reciprocatory movements. The cam-wheel 159 is fixed upon the transverse shaft 162 mounted in bearings 163 parallel with the rock-shaft 153 and carrying upon its rearward end the spiral gear 164 meshing with the similar gear 165 upon the upper end of a vertical shaft 166 which carries at its lower end another spiral gear 167 meshing with a spiral gear 168 which is fixed upon the main-shaft 5. By the connections just described, the shaft 162 has rotary movements 10 imparted to it in unison with those of the main or driving shaft.

Adjustably secured upon the forward end of the hammer rock-shaft 153 by means of the set-screw 169 is the hub 170 of a rigid arm 171 carrying at its outer extremity a hook 172 to which is attached one end of a spring 173 whose opposite end is connected to a hook 174 secured to the bed 3. While the hammer-head would naturally fall by 25 gravity as the wearing plate 158 rides successively over the teeth 160 of the hammer-retracting cam-wheel 159, the spring 173 not only assists the hammer in performing its falling or operative movements, but affords a means of adjustment of the intensity 30 of the hammer-stroke by the shifting of the arm 171 upon the hammer rock-shaft. The effect of the spring 173 combined with the action of gravity upon the hammer-head 35 produces upon the straightening member a peening impact.

Adjustably secured upon the hammer rock-shaft 153 by means of the set-screw 175 is the hub 176 of a striker-arm 177 40 which is connected with a laterally extending wing 178 of the hub 151 by means of the adjusting push- and pull-screws 179 and 180, respectively, the former being tapped through the wing 178 and having its point 45 resting upon the top of the arm 177 and the latter passing through the wing 178 and being tapped into the arm 177. The lower operative edge 177^a of the arm 177 is slightly inclined upwardly and in the operative 50 movements of the hammer is adapted to engage the correspondingly inclined upper operative face 181 (Fig. 6^a) of a sliding wedge-block 182 constituting the active member of the impact-regulator resting 55 upon the flat upper face of the supporting block 183 which is secured upon a horizontal member 184 of the bracket 155 and provided with the undercut guide-strips 185 embracing the lateral flanges 182^a of the 60 wedge-block for which they afford, in conjunction with the block 183, a slideway transverse to the rock-shaft 153. By temporarily loosening the set-screw 175 and successively turning the adjusting screws 65 179 and 180, the position of the arm 177

may be adjusted relatively to the hammer helve 149, whereby the normal advance or straightening position of the nose of the hammer 145 will be determined when the wedge-block 182 is in initial position, the latter serving to arrest the downward movement of the hammer-head under the action of gravity and the spring 173.

The wedge-block 182 is formed with the spaced ears 186 between which is pivotally secured by means of the pin 187 one of the eyed ends of a connecting rod 188 whose opposite end is connected by means of the pin 189 with the forked upper end of an arm 190 whose hub is fixed adjustably by 80 means of the set-screw 191 upon the feeler rock-shaft 192 having conical-pointed extremities entering corresponding sockets in the bearing screws 193 tapped respectively through the spaced members 194 of a bearing yoke extending laterally from the anvil-supporting block and provided with the set-nuts 195. Fixed upon the shaft 192 by means of the set-screw 196 is a block 197 having extending therefrom toward the anvil the rigid arm 198 having at its outer end the enlargement 199 slightly offset upwardly to form the lower jaw of the feeler. The top of the block 197 affords a flat seat 200 upon which is secured by means of the screws 201 passing through it and tapped into the block 197 the end portion 202 of a lateral arm 203 overlying the arm 198 and having secured at its outer end by means of the screw 204 the block 205 which affords the upper jaw of the feeler between which and the lower jaw 199 the portion of the needle adjacent and beyond the anvil from the hammer path projects in a direction substantially parallel with the feeler arms.

Secured by means of the set-screw 206 upon the feeler-shaft 192 intermediate the block 197 and the hub of the upright arm 190 is the hub 207 of a lateral arm 208 carrying the counter-balance weight 209 secured thereon by the set-screw 210, the weight being adjusted to counteract the weight of the lateral arms 198 and 203 so that the several members carried by the rock-shaft shall 110 have no resultant turning moment, and the feeler is made substantially a floating member adapted to follow with the greatest freedom and precision the eccentricities of the needle-blade while the latter rotates. Beyond the block 197 the rock-shaft 192 has secured thereon by means of the set-screw 211 the hub 212 of a depending arm 213 whose split lower end portion 214 is transversely apertured to receive the stop-screw 120 215 which is held against turning by means of the clamp-screw 216 passing through the lower end of the part 214 of the depending arm 213, the point of the screw 215 resting against the adjacent face of the anvil-block 125 130

132. By the means just described, the range of upward movement of the feeler-jaws is limited, while the needle resting in contact with the anvil 136 affords a limit of movement therefor in the reverse direction.

133. The parts are so proportionate and arranged that when the portion of the needle-blade embraced by the feeler jaws is concentric with the axis of rotation of the 10 needle-chuck, the feeler rock-shaft 192 is so held by the lateral arms 198 and 203 that the wedge-block 182 is maintained in normal position beneath the striker-arm 177, and the minimum stroke for which the hammer 15 is adjusted is imparted to the same. As a crook or bend in the needle enters the feeler-jaws, the feeler-arms are forced downwardly and the wedge-block is withdrawn from initial position to permit the increased stroke 20 of the hammer which strikes the needle-blade upon the opposite side of the anvil and thrusts the adjacent portion downwardly, which causes the portion embraced by the feeler-jaws to assume temporarily an 25 upward inclination at the opposite side of the anvil. As the needle revolves and recedes from initial advance straightening position, the blows of the hammer are regulated to deliver graduated peening impacts 30 upon the needle-blade so as to reduce and remove the lateral deflections or eccentricities therein. As the feeler rests in contact with the same bend of the needle-blade struck by the hammer and simultaneously 35 with the straightening impacts thereon, it is evident that the impact-regulator connected therewith serves to control with the utmost precision the straightening effect of each of the hammer blows. As each of the 40 feeler-blocks 199 and 205 is adapted to contact with the needle, it is evident that either of these feeler-elements may be employed and the other dispensed with without serious detriment to the control of the hammer; and 45 it has been found in practice that the lower of these elements will satisfactorily perform the function of the feeler without means other than the counter-weight 209 or an equivalent spring for maintaining it in operative relation with the under side of the 50 needle-blade. As the hammer strokes should cease during the retraction of the needle-chuck and renewal of needles therein and advance of the same for a succeeding 55 straightening operation, the bed 3 is provided with a tubular standard 217 affording a bearing for a vertically movable stop-bar 218 whose upper end is adapted to engage the hammer helve 149 intermediate its ends, 60 and its lower end rests upon the periphery of a cam-disk 219 whose hub 220 is fixed by means of the set-screws 221 upon the cam-shaft 39. At the desired point of the machine cycle, after the point of the needle 65 has advanced across the anvil, the stop-bar

218 is permitted to descend to permit the wearing plate 158 to resume operative relation with the hammer-lifting cam 159, the bar 218 remaining in lower position until the completion of the straightening operation and the needle has been retracted to bring its eye above the anvil, after which the bar 218 rises under the action of the cam 219 and the hammer helve 149 is lifted sufficiently to retract the wearing plate 158 above the range of movement of the cam 159. As indicated in dotted lines in Fig. 1, the stop-bar 218 is prevented from turning within the standard 217 by means of the spline 218.

70 The feed-cam is formed to produce a varied-motion feed, the cam-cylinder 38 having secured upon its periphery for the purpose the spaced cam-plates 38^x and 38^y, the edges of which are engaged by the roller 36 carried by the stud 35 depending from the carriage. As represented diagrammatically in Fig. 13, the operative edge of the cam-plate 38^x is formed with a straight portion 37^a to afford the initial dwell for presentation of the needle-blade adjacent the shank to the hammer for a succession of concentrated straightening blows in the advance position of the needle over the anvil, an inclined portion 37^b for producing the lengthwise feed of the needle for distribution of the hammer-blows along the needle-blade, and a straight portion or dwell 37^c for arresting or materially retarding the feed of the needle to present that portion of the 100 blade adjacent the eye for the final concentrated series of hammer blows. After the arrest of the hammer reciprocations, the roller 36 engages the abruptly inclined portion 37^d of the cam edge for production of the final retrograde movement of the needle to extreme retracted position wherein it is permitted to remain by reason of the straight portions 37^e of the adjacent edges of the cam-plates 38^x and 38^y while the straightened needle is released from the chuck or holder and an unstraightened needle is inserted therein, after which the traverse of the roller 36 in engagement with the abruptly and reversely inclined cam edge portion 37^f of the cam-plate 38^y causes the advance of the needle to extreme position over the anvil wherein it is permitted to remain while the roller 36 traverses the straight portion of the groove afforded by the substantially parallel adjacent edges 37^a of the two cam-plates 38^x and 38^y for reception of the initial series of straightening blows adjacent the shank. The dwell portions 37^a and 37^c while represented as disposed in planes 115 slightly inclined to each other and one of them perpendicular to the axis of the cam-cylinder 38, are not necessarily so arranged, as the degree of concentration of the initial 120 and final series of straightening blows near 130

the shank and the eye of the needle, respectively, may obviously be varied to suit the character of the needles, as regards size and temper. The rotation of the needle combined with its endwise travel thus produces a helical feeding movement before or in front of the hammer having a pitch with dwells therein caused by the dwell portions 37^a and 37^c of the cam for interruption of 5 the axial movement while the circular movement continues. During each rotation of the needle the series of regulated blows of the hammer are delivered in quick succession, there being as high as six or more hammer-impacts on each rotation of the needle.

10 The hammer in the present embodiment of this invention operates as an impact-straightener in its delivery of quick or instantaneous blows to the needle to be straightened, in distinction from pressure straighteners such as those employed in straightening heavy and untempered rails or bars by application of gradual bending strains thereon. It is obviously immaterial 15 whether the lengthwise movements of the needle derived from the feed-cam be imparted to the needle-carriage or to the hammer and adjacent anvil, as the straightening action will be the same in either case.

20 As represented, more particularly in Fig. 12 the projection 219^c of the cam 219 for engagement with the stop-bar 218, is arranged in register with the portions 37^a, 37^c and 37^t of the feed-cam groove or path-way 25 in order that the action of the hammer may be interrupted while the needle-holding chuck discharges a straightened needle and receives an unstraightened needle and while 30 it is moving backwardly from the final 35 straightening position and advancing to extreme initial straightening position relative to the anvil. The cam 219 is preferably so adjusted upon the supporting shaft 39 that the period of action of the hammer is timed 40 for the production of a slightly greater number of impacts near the eye than near the shank.

45 It is necessary that the rotation of the needle-chuck should cease after each straightening operation to bring the chuck-jaws 50 into register with the spring-jaws of the needle-hopper and maintain them in such relation during the discharge of a straightened needle and introduction of a succeeding unstraightened needle. To this end, the 55 fixed bushing 80 upon the chuck-spindle 46 is provided upon the outer face with two lugs 222 which are adapted to be engaged by the projecting nose 223 of a stop-bolt 60 224 mounted in a suitable transverse guideway in a standard 225 secured upon the base-plate 27 of the chuck-carriage by means of screws 226. The standard 225 has a slot 227 through which passes a laterally projecting stud 228 carried by the stop-bolt 224,

which stud is adapted for engagement by the spaced members 229 of the upwardly extending arm 230 of an angle-lever fulcrumed by means of the stud-screw 231 upon the standard 225 and having a laterally extending wedge-pointed arm 232 adapted for engagement alternately with the opposite faces of the wedge-pointed plug 233 fitted within a transverse socket 234 formed therefor in the base of the standard 225 with its reduced shank 235 passing through an aperture in the plug 236 at the inner end of the socket, between which and the enlarged forward end of the plug 233 is interposed the spring 237 by 70 which the plug is yieldingly maintained in operative relation with the arm 232 of the angle-lever, so that the latter is maintained by the action of the spring 237 in one or the other of its extreme positions, whereby 75 the nose 223 of the stop-bolt is held in extreme advance or operative position within the path of movement of the studs 222, as represented in Fig. 4, or wholly retracted 80 therefrom so as to permit the studs 222 to 85 freely pass the end of the stop-bolt. In the position of the stop-bolt represented in Fig. 4, the nose 223 thereof is in positive engagement with a stud 222 of the bushing 80, and the chuck-spindle 46 is restrained 90 from movement in needle-clamping and -unclamping position, while the grooved pulley 34 is permitted to continue its rotation under the action of its driving belt.

95 The stop-bolt operating angle-lever has a 100 rearwardly extending arm 238 provided with a socket in which is secured by means of the set-screw 239 the stem 240 of a rearwardly extending ball-stud 241 which is carried by the chuck-carriage into engagement with a substantially lozenge-shaped cam-block 242 having a lateral boss 243 which is journaled in the upright member 244 of a bracket whose foot 245 is suitably secured upon the machine bed, the inner 105 extremity of the boss 243 being provided with a diametrical tongue 246 to which is fitted the cross-bar 247 which is secured thereon by means of the screw 248. As before indicated, the cam-block 242 has the 110 general form of a rhombus, and two of the opposite edges are flat adjacent the outer extremities and formed with curved shoulders 249 terminating slightly beyond the axis of the boss 243. The upper end of the 115 cross-bar 247 is limited in its vibratory movements by engagement with the points of the stop-screws 250 and 251 tapped into the spaced lugs 252 laterally offset from the bracket-member 244 and secured in position by means of the set-nuts 253, and such cross-bar is normally maintained in contact with the stop-screw 250 by means of a 120 spring 254 having one end secured by means of a screw 255 upon the foot of the bracket- 125 130

piece and the other end engaged by a hook 256 at the extremity of the lower arm of the cross-bar 247.

As represented in the drawings, the chuck-carriage is in retracted position with the stop-bolt operating angle-lever tilted upon its fulcrum for maintenance of the stop-bolt in advance or chuck-spindle arresting position, and the ball-stud 241 in upper retracted position above the fulcrum 243 of the cam-block 242. After the discharge of the straightened needle and introduction of the new needle, the needle-hopper is raised under the action of the cam 122 and the chuck-carriage begins its advance under the action of the cam 38. The ball-stud 241 is thereby carried beneath the upper point of the cam-block 242 and rides down the inclined under side of the same until it reaches the shoulder 249, when it tilts the cam-block temporarily in opposition to the spring 254, and is at the same time pressed downwardly so as to throw the angle-lever arm 238 below the fulcrum-stud 243, which brings the nose of the arm 232 upon the opposite side of the point of the holding plug 233, whose spring causes the shifting of the angle-lever, and hence of the arm 230 into extreme retracted position, and the engagement of one of the members 229 of such arm with the stud 228 of the stop-bolt by means of which the latter is retracted to inoperative position and the chuck-spindle released for rotation with the pulley-wheel 84. The pulley-wheel continues its rotation during the advance of the chuck-carriage and the return feed of the latter while the hammer performs its function, but as the carriage approaches extreme retracted position, the ball-stud 241 rides up the inclined edge of the cam-block 242 adjacent the lower point and engages the shoulder 249, which tilts the cam-block to disengage the same, and at the same time rocks the stop-bolt operating angle-lever to throw the same into the other extreme position, which causes the advance of the stop-bolt into operative position and the consequent arrest of the rotation of the chuck-spindle, as before described. It will be observed that after each engagement of the ball-stud 241 with the oscillating cam-block 242, the spring 254 causes the return of the latter to initial position with its lower end inclined downwardly and forwardly in the direction of advance of the chuck-carriage.

The machine bed 3 is provided with an aperture substantially beneath the needle-hopper through which passes the spout 257 of a receptacle 258 secured by means of the standard 259 and screws 260 upon the top of the bed and adapted to catch the needles as they are discharged by the chuck and convey them into a tray supported upon the base 1

of the machine. The tray is shown herein comprising a rectangular box 261 divided longitudinally into two compartments by means of the partition 262, and each compartment is divided into a series of smaller compartments by means of a division-plate 263 with the U-shaped partition members 264 forming needle-receiving compartments adapted to receive successively a predetermined number of needles as they are delivered from the spout 257. The tray rests upon the inclined traveling platform 265 upon which it is held in place by means of the casing 266 embracing the front side and the opposite ends and itself held in position by means of steady pins 267 secured to the ends and projecting downwardly through two sets of holes 268 provided therefor in the platform. Either of the two rows of needle compartments may be brought into register with the lower end of the spout 257 by shifting the case 266 to bring its steady-pins 267 into register with the corresponding pair of apertures 268 in the platform 265. The platform is provided upon its under side and near the inner edge with two parallel ribs 269 to form a groove which is entered by the top of a longitudinally extending guide-rail 270 secured upon the base-plate 1 by means of the screws 271. The rail 270 affords a support and guide for the inner portion of the platform 265 whose outer or forward edge rests upon the top of the base-plate 1. To the bottom of the platform 265 is secured by means of screws 272 the plate 273 having its edge formed with ratchet-teeth 274 projecting beyond the inner edge of the platform and engaged by the forked operative end 275 of a pawl-lever 276 pivotally connected by means of the stud-screw 277 to a boss 278 at one end of a rock-lever 279 fulcrumed upon a stud-screw 280 and carrying at its opposite end a stud 281 adapted for engagement with a laterally projecting cam-tooth 282 upon a plate 283 secured by means of screws 284 within a recess in the face of a pin-wheel 285 mounted by means of a stud-screw 286 upon a standard 287 having its foot 288 secured by means of bolts 289 upon the base-plate 1 and into which the fulcrum-stud 280 of the rock-lever 279 is tapped. The stud 281 of the rock-lever 279 is normally maintained in operative relation with the pin-wheel 285 by means of a spring 290 having one end secured to a hook 291 near the opposite end of said lever and the other end secured by a screw 292 to the base-plate 1; while the pawl-lever 276 is yieldingly maintained in operative relation with the rack-teeth 274 carried by the traveling platform by means of a spring 293 having one end connected with a hook 294 thereon and the other end secured by a screw 295 upon the foot of the rail 270.

The pin-wheel 285 has projecting from

the face opposite the cam-tooth 282 a circular series of pins 296 adapted to be successively engaged by a substantially radial tooth 297 upon a plate 298 secured by screws 299 upon the face of a ratchet-wheel 300 mounted upon a screw-stud 301 tapped into the standard 287 and having its peripheral teeth in operative relation with a reciprocating pawl 302 pivotally mounted upon a pin 303 at one end of a rock-lever 304 mounted upon a fulcrum-pin 305 carried by a bracket-piece 306 attached to the bottom of the bed 3, the downwardly curved opposite end of the rock-lever resting upon the cam-cylinder 307 fixed upon the cam-shaft 39 and provided at one point in its periphery with a cam-projection 308 adapted to tilt the rock-lever 304 once for each rotation of the cam-shaft to advance the ratchet-wheel 300 one tooth in its step-by-step rotation. The pawl 302 is maintained in contact relation with the toothed periphery of the ratchet-wheel 300 by means of a spring 309 connected with the same at one end and at the opposite end with a hook 310 carried by the bed 3; and the ratchet-wheel is restrained against retrograde movement by means of a spring-detent 311 secured by means of a screw 312 upon the top of the standard 287. As herein represented, the ratchet-wheel 300 has twenty teeth and the pin-wheel 285 has ten lateral pins, and it will therefore be seen, that for each complete rotation of the pin-wheel 285 and consequently for each engagement of the cam-tooth 282 with the stud 281 of the rock-lever 279, the cam-shaft 39 makes two hundred complete rotations, each rotation marking the completion of a needle-straightening operation; and as the ratchet-teeth 274 upon the platform 265 are of a length equal to the width of the smaller needle-compartments of the tray, it will be seen that each actuation of the rock-lever 279 after the straightening of every two hundred needles will impart to the tray a lateral movement to bring a different unfilled needle-compartment in register with the spout of the needle receptacle 258 so that each needle compartment will have delivered thereto a predetermined number of needles, in the present instance 200.

As the needle-hopper sustaining arm 99 is secured upon the rock-shaft 102 by a set-screw 101, it will be observed that the operative positions of the needle-holding jaws 96 for delivery of needles to the chuck-jaws may be adjusted by properly setting the arm 99 upon the rock-shaft, but to adjust the needle-shank holding jaws 96 with greater nicety relatively to the chuck-jaws, adjusting means are shown in connection with the link 115. To this end, the link 115 has secured thereto by means of the screw-stud 313 a block 314 carrying the adjusting screw 315 whose point is adapted to rest

upon a lug 316 projecting from the top of the bed 3, this adjusting screw being provided with a set-nut 317 for maintaining it in position. The needle-hopper sustaining arm 99 having been adjusted upon the rock-shaft 102 into approximately the right position, the final adjustment is made by means of the adjusting screw 315 to properly locate the sustaining pin 114 for the rock-shaft arm 124 so as to cause the spring-holding jaws 96 to accurately register with the chuck-jaws when delivering needles thereto, the elevation of the link in such case causing the pin 121 of the lever 117 to be arrested in its downward movement somewhat above the bottom of the notch 123 when the needle-hopper is moved into operative position.

In preparing the machine for operation, the anvil 135 is adjusted toward or from the axis of the chuck-spindle by manipulation of the adjusting screws 142 and 144 to shift the wedge-plate transversely of the machine, the operative edge 136 of the anvil being properly set at one side of and slightly more than a half-diameter from said axis of rotation suitable for operation upon the size and temper of the needle to be straightened. The hammer-head 148 is also adjusted upon the helve 149 to bring its path of movement at the required distance from the face of the anvil to give the desired degree of abruptness in the bend of the needle imparted by the hammer blows. While the feeler-arms are in the normal position which they assume in embracing a perfectly straight needle, the wedge-block 182 assumes an initial position nearest the hammer-rock-shaft 153. The inclined lower edge 177^x of the striker-arm 177 affords a seat for contact with the wedge-block, and while such parts are in operative relation, in the initial position of the wedge-block and while the machine is at rest, the adjusting screws 179 and 180 are manipulated to adjust the nose of the hammer in normal advance or straightening position so as to just touch the upper side of a straightened needle, and the arm 171 is so set upon the hammer-rock-shaft as to adjust the spring 173 to impart, in conjunction with the weight of the hammer, the requisite intensity of blow for the work to be performed. Preparatory to starting the machine, the chuck-carriage is retracted and the chuck-jaws are opened, the rotation of the chuck-spindle being arrested by the operative engagement of the stop-bolt 224 with the lug 222, and the hammer movements being arrested by the elevation of the stop-bar 218 to lift the hammer out of operative relation with its actuating cam 159. As the machine is started, the needle-hopper descends and places its lowermost needle, yieldingly held by the spring-jaws 96, between the chuck-jaws 55, which close thereon after which the needle-hopper

rises and the succeeding needle enters the spring-jaws 96 for subsequent delivery to the chuck. As the carriage begins its advance the stop-bolt 224 is retracted to permit the rotation of the chuck-spindle with the pulley 84, and during the dwell of the chuck at extreme advance position, the stop-bar 218 descends and the hammer begins its action to deliver its initial series of straightening blows upon the needle-blade near the shank. As the carriage performs its return needle-feeding movement under the action of the cam 38 its travel is much slower than its advance, and the hammer continues its action upon the needle with blows of varying intensity under the influence of the shifting wedge-block governed by the feeler whose jaws closely embrace the needle and follow its deflections from the normal axial line. The straightening action continues until the needle has receded so far as to bring its eye nearly or quite to the operative edge of the anvil, when the final series of concentrated straightening blows is delivered, after which the rise of the stop-bar 218 interrupts the hammer blows and the return of the needle to initial retracted position is effected without further operation of the hammer thereon. As the carriage nears its retracted position, the stop-bolt 224 is again advanced toward the chuck-spindle and its engagement with one of the lugs 222 arrests the chuck with its jaws 55 in horizontal position, as represented in the drawings, after which the advance of the release rod 62 under the action of the cam 79 causes the opening of the chuck-jaws and discharge of the needle into the receptacle 258 by means of which it is directed into the proper compartment of the needle-tray.

It will be observed that the hammer, comprising the helve 149 and head 148 with its nose 145, is self-acting, in that the lifting cam 159, elsewhere herein termed its "actuating means", serves merely to retract and release it, the operative movement of the hammer being produced partly by gravity and partly by the spring 173.

The impact-regulating wedge-block 182 is normally set, in the present embodiment of the invention, to sustain the nose of the hammer spaced slightly above the blade of a perfectly straight needle when at rest, and thus the hammer-holder hits the wedge-block before the hammer-head hits the needle. The overthrow of the hammer-head from normal arrested position in order to produce the impact results from the resilience of the helve or holder in conjunction with the momentum of the hammer-head in dropping from retracted position under the action of the cam-wheel or trip 159.

By reference to the drawings, it will be observed that the points of contact of the hammer and feeler are spaced apart length-

wise of the needle, not only for location of the anvil between them, but to insure effectiveness in the control of the hammer blows. As is well known to needle manufacturers, one of the effects of the hardening operation upon a previously grooved needle is to produce a curvature therein in the plane of the axis of the needle and toward its grooved side, the deflection of the needle blade in such direction being progressive from near its junction with the shank, and therefore greater in the eyed and pointed portion. As the feeler is not only spaced from, but is disposed nearer the needle point than the hammer, it has a greater traverse, and is thus far more sensitive in its control of the impact-regulating wedge-block than if it were disposed close to the impact point or on the shank side thereof. This comparatively wide latitude of operation of the feeler is obviously facilitated by the setting of the anvil slightly below the lower side of a straightened needle, thereby permitting an unstraightened needle to perform unrestrictedly a gyratory movement which is followed in the vibratory movements of the feeler-arms 198 and 203.

It is obvious that the operation of the straightening mechanism would not be materially affected by the addition of a needle-support or secondary anvil disposed intermediate the path of the hammer and the chuck for the purpose of relieving the latter from the effect of the impact of the hammer upon the needle; as in such case the effective bending operation for straightening the needle-blade would still be performed by the hammer in conjunction with the anvil located farthest from the needle-chuck. As the object in interrupting the rotation of the chuck is merely to provide for the lateral discharge and introduction of needles, it is evident that the rotation arresting means would not be required were the needles introduced axially through a tubular chuck-operating rod 62, as has been proposed heretofore in connection with needle-holding chucks.

From the foregoing description it will be observed that the method of endwise movement of the needle, or the character of its movement toward the anvil under the action of the feed-cam 38, is the same for each needle-straightening cycle, whether such movement be uniform or variable. It will also be observed that, whether the hammer-movements be of uniform or variable frequency, they are in the present machine controlled as to frequency independently of the character or condition of the needle to be straightened, and are therefore of predetermined number in each needle-straightening cycle, whereby each straightening movement of the hammer is caused to have a fixed and predetermined relation with the position of

the movable needle-support or chuck at each stage of the successive needle-straightening operations. Therefore, the feeding movements and hammer-strokes are timed precisely the same for a succession of needles acted upon by the machine, the only variations in the action of the machine upon successive needles being in the character of the hammer-impact under the control of the 10 feeler conforming in its operative movements with the degree of deflection of the needle.

Having thus set forth the nature of the invention, what I claim herein is:—

15 1. In a needle-straightening machine, the combination with a plurality of supports upon which the needle rests leaving an unsupported portion between them, of an impact-straightener operating upon said unsupported portion between said supports, and means whereby continuous turning movements are imparted to the needle throughout the straightening operation.

20 2. In a needle-straightening machine, in combination, a support for the unpointed end of the needle whereby continuous turning movements are imparted to the needle, a second support leaving an unsupported portion of the needle between it and the 30 first support, an impact-straightener operating upon said unsupported portion of the needle between said supports, and means whereby said first support is moved backward and thereby draws the needle endwise 35 past said second support and said impact-straightener.

3. In a needle-straightening machine, in combination, an anvil, a hammer, means whereby the forward position of the hammer when at rest may be adjusted at a point 40 slightly more removed from the plane of the anvil than the diameter of the needle-blade, and means controlled by an element contacting with the needle upon the opposite side of the anvil from the hammer whereby the intensity of the hammer action 45 is regulated.

4. In a needle-straightening machine, in combination, an anvil, a hammer, a trip for 50 alternately retracting and releasing said hammer, and means whereby the needle-blade is normally held so that when straight it will be slightly out of contact with the anvil.

55 5. In a straightening machine, in combination, a plurality of separated needle-supports, a straightener operating between the same, and a device whereby a helical feeding movement relative to said straightener 60 is imparted to the needle, and means whereby dwell in pitch is produced for a portion of said movement.

6. In a straightening machine, in combination, a plurality of separated supports, a 65 straightener operating between the same,

and a feeding device acting upon the needle to move its blade past said straightener; and having means for retarding the movement of the needle when its eyed portion is in operative relation with the straightener. 70

7. In a straightening machine, in combination, a plurality of separated supports, a straightener operating between the same, and a feeding device acting upon the needle to move its blade past said straightener and 75 having means for retarding the movement of the needle when the portions near the shank and eye, respectively, are in operative relation with the straightener.

8. In a straightening machine, the combination with needle-supporting means, of a hammer, an impact-regulator therefor, and means contacting with the needle at a distance greater than the diameter of the latter from the impact-point of the hammer 85 for controlling the action of said impact-regulator.

9. In a straightening machine, the combination with needle-supporting means and a hammer, of a trip acting upon said hammer, 90 and an automatic impact-regulator for said hammer.

10. In a straightening machine, the combination with a plurality of separated supports, of an impact straightener operating 95 between the same and constantly close to one thereof, means for separating said supports, and means for imparting to the article to be straightened turning movements bearing a fixed relation to the frequency of 100 the impacts of said straightener.

11. In a straightening machine, the combination with needle-supporting means, of a hammer, an automatically acting impact-regulator therefor comprising an adjustable 105 stop and a trip for said hammer.

12. In a straightening machine, the combination with needle-supporting means, of a hammer, an automatically acting impact-regulator therefor independent of the same, 110 and a feeler whereby said regulator is controlled by the eccentricities of the needle contacted by said feeler.

13. In a needle-straightening machine, in combination, needle-turning means, a feeler 115 embracing the needle, and an impact regulator mechanically connected therewith.

14. In a straightening machine, the combination with an anvil, of a hammer and a feeler on opposite sides of said anvil, and an 120 impact-regulator controlled by said feeler.

15. In a straightening machine, the combination with needle-supporting means, of a hammer, an automatically acting impact-regulator therefor, and a feeler supported 125 independently of the hammer for controlling said regulator and contacting with the needle upon opposite sides of its blade.

16. In a straightening machine, the combination with needle-supporting means, of 130

- a hammer, a feeler supported independently of the hammer and contacting with the needle upon the same side thereof as the hammer, and an impact-regulator controlled by the feeler. 5
17. In a straightening machine, the combination with needle-supporting means, of a hammer, a feeler supported independently of the hammer and contacting with the needle simultaneously with the hammer, and an impact-regulator controlled by the feeler. 10
18. In a straightening machine, the combination with needle-supporting means, of a hammer and a feeler contacting with the same bend of the unstraightened needle at different longitudinal points at a substantial distance apart, and an impact-regulator controlled by the feeler. 15
19. In a straightening machine, the combination with needle-supporting means, of a hammer, an impact-regulator therefor, and a substantially floating feeler contacting with the needle-blade and adapted to control the impact-regulator. 20
20. In a needle-straightening machine, in combination, a feeler, an impact-regulator, connecting mechanism, and a substantially unitary support for said feeler and connecting mechanism. 25
21. In a needle-straightening machine, in combination, a feeler containing two contact members, means for adjusting one of said contact members toward and from the other, and an impact regulator connected with said feeler. 30
22. In a needle-straightening machine, in combination, a feeler contact member, a pivotally mounted arm supporting the same independently of the hammer and an impact regulator mechanically connected therewith. 35
23. In a needle-straightening machine, in combination, a feeler contact member, an arm supporting the same and extended endwise of the needle and an impact regulator connected therewith. 40
24. In a needle-straightening machine, in combination, a feeler containing two contact members, arms respectively supporting the same and between which arms the needle projects, and an impact regulator connected with said arms. 45
25. In a straightening machine, the combination with needle-supporting means, of an anvil disposed at one side of the needle, a reciprocating hammer having a path of movement adjacent said anvil and intermediate the latter and the needle-supporting means, actuating means for said hammer, and means for producing between the needle and the hammer relative feeding movements lengthwise of the needle and simultaneous turning movements. 50
26. In a straightening machine, the combination with needle-supporting means, of an anvil disposed at one side of the needle, a self-acting reciprocating hammer having a path of movement adjacent said anvil and relatively remote from the needle-supporting means but intermediate the latter and the anvil, positively acting mechanism for successively retracting and releasing said hammer to permit the same to strike the needle at a point adjacent the anvil, and means for producing between the needle and the hammer relative feeding movements lengthwise of the needle. 55
27. In a straightening machine, the combination with an axially moving needle-chuck and actuating means therefor, of an anvil disposed eccentrically to the axis of said chuck, a reciprocating hammer having a path of movement adjacent said anvil and relatively remote from the needle-chuck but intermediate the latter and the anvil, and actuating means for said hammer. 60
28. In a straightening machine, the combination with a rotary and axially moving needle-chuck and means for imparting axial movements thereto, of an anvil disposed eccentrically to the axis of rotation of said chuck, a reciprocating hammer having a path of movement adjacent said anvil and relatively remote from the needle-chuck but intermediate the latter and the anvil, actuating means for said hammer, and means for continuously rotating said chuck during the period of operation of the hammer. 65
29. In a straightening machine, the combination with needle-supporting means, of an anvil disposed at one side of the needle, a reciprocating hammer having a path of movement adjacent said anvil, actuating means for said hammer, and an impact-regulator mechanically actuated by the deflection of the needle from its axis whereby the impact of the hammer is determined. 70
30. In a straightening machine, the combination with needle-supporting means, of an anvil disposed at one side of the needle, a reciprocating hammer having a path of movement adjacent said anvil and intermediate the latter and the needle-supporting means and provided with means for lateral adjustment toward and from said anvil, and actuating means for said hammer. 75
31. In a straightening machine, the combination with needle-supporting means, of an anvil disposed at one side of and provided with means for its adjustment toward and from the needle, a reciprocating hammer having a path of movement adjacent said anvil and intermediate the latter and the needle-supporting means, and actuating means for said hammer. 80
32. In a straightening machine, the combination with needle-supporting means, of an anvil disposed at one side of the needle, a rock-shaft, a hammer comprising a helve 85

fixed upon said rock-shaft and having a hammer-head with a path of movement adjacent said anvil and formed with a seat distant from said rock-shaft, actuating 5 means for said hammer, a stop-member having an operative face disposed in the path of movement of said seat of the hammer-helve, and adjusting means for said stop including a controlling member engaging the 10 needle and actuated by the deflection of the same from its axis whereby the impact of the hammer is varied.

33. In a straightening machine, the combination with needle-supporting means, of 15 an anvil disposed at one side of the needle, a rock-shaft, a hammer comprising a helve fixed upon said rock-shaft and having a hammer-head with a path of movement adjacent said anvil and provided with a lateral 20 wing affording a seat distant from said rock-shaft, a peripherally toothed actuating cam for alternately retracting and releasing the hammer-helve preparatory to each operative stroke of the hammer, a wedge-block sup- 25 ported within the path of movement of said wing and movable toward and from said rock-shaft and having an inclined face adapted for contact with the seat of said wing of the hammer-helve, and adjusting 30 means for said wedge-block controlled by the deflection of the needle from its axis.

34. In a straightening machine, the combination with needle-supporting means, of 35 an anvil disposed at one side of the needle, a rock-shaft, a hammer comprising a helve fixed upon said rock-shaft and having a hammer-head with a path of movement adjacent said anvil, said helve being provided with a seat remote from said rock-shaft and 40 with means for adjustment of said seat in the direction of its movement upon said rock-shaft, actuating means for said hammer, a stop-member having an operative face disposed in the path of movement of 45 said seat of the hammer-helve, and adjusting means for said stop-member including a controlling member engaging the needle and actuated by the deflection of the same from its axis whereby the hammer-stroke is varied.

50 35. In a straightening machine, the combination with needle-supporting means, of an anvil disposed at one side of the needle, a rock-shaft, a hammer comprising a helve fixed upon said rock-shaft and having a 55 hammer-head with a path of movement adjacent said anvil and provided with a lateral wing in substantially radial relation with said rock-shaft, a member connected with one face of said wing and adjustable to- 60 ward and from the same and provided with a contact-seat, actuating means for said hammer, a stop-member having an operative face disposed in the path of movement of said contact-seat, and adjusting means 65 for said stop-member including a control-

ling member engaging the needle and actuated by the deflection of the same from its axis whereby the hammer-impact is varied.

36. In a straightening machine, the combination with needle-supporting means, of 70 an anvil disposed at one side of the needle, a reciprocating hammer having a path of movement adjacent said anvil, actuating means therefor, and means independent of said actuating means for varying the impact 75 of the hammer.

37. In a straightening machine, the combination with needle-supporting means, of 80 an anvil disposed at one side of the needle, a horizontally disposed hammer-rock-shaft, a hammer comprising a laterally extending helve fixed upon said rock-shaft and a hammer-head carried by said helve and moving in a path adjacent said anvil, means for alternately lifting and releasing said hammer, and a spring acting in opposition to the hammer-lifting means whereby a peening action is imparted to the hammer. 85

38. In a straightening machine, the combination with needle-supporting means, of 90 a hammer, a vibratory holder therefor provided with a shoulder, a fixed stop-member toward and from which said shoulder moves, a movable stop-member interposed between the fixed stop-member and said shoulder 95 and movable toward and from the axis of motion of said holder, and shifting means for said movable stop-member.

39. In a straightening machine, the combination with needle-supporting means, of 100 an anvil disposed at one side of the needle, a hammer-rock-shaft, a hammer comprising a helve fixed upon said rock-shaft and a hammer-head carried by said helve and moving in a path adjacent said anvil, means 105 for alternately lifting and releasing said hammer, a spring acting in opposition to the hammer-lifting means, whereby a peening action is imparted to the hammer, and independent means for varying the extent 110 and force of the hammer action.

40. In a straightening machine, the combination with needle-sustaining means, of 115 an anvil disposed at one side of the needle, a reciprocating hammer moving in a path adjacent said anvil, means for producing between the needle and the hammer relative feeding movements lengthwise of the needle, actuating means for said hammer, and hammer arresting means for interrupting the 120 operation of the hammer while the needle-supporting means and the hammer are farthest separated in the relative positions occupied substantially at the completion of 125 a feeding movement.

41. In a straightening machine, the combination with needle-supporting means, of an anvil disposed at one side of the needle, a reciprocating hammer moving in a path 130 adjacent said anvil, actuating means for

- said hammer, a hammer-arresting member, and means for shifting the same into operative relation with the hammer for retracting the latter from the range of action of its actuating mechanism.
42. In a straightening machine, the combination with needle-supporting means, of an anvil disposed at one side of the needle, a reciprocating hammer moving in a path adjacent said anvil, means for producing between the needle and the hammer relative feeding movements lengthwise of the needle, actuating means for alternately retracting and releasing said hammer to enable it to perform its operative movements, a hammer-arresting member normally out of the range of movement of said hammer, and actuating means therefor acting when the needle-supporting means and the hammer are relatively in substantially extreme retracted position and adapted to shift said arresting member for retraction of the hammer out of the range of movement of its actuating means.
43. In a straightening machine, the combination with needle-supporting means, of an anvil disposed at one side of the needle, a hammer-rock-shaft, a self-acting hammer comprising a helve fixed upon said rock-shaft and a hammer-head carried by said helve and moving in a path adjacent said anvil, a rotary peripherally-toothed cam for alternately retracting and releasing said hammer to enable it to perform its operative movements, an arresting member normally out of the range of movement of the hammer-helve, and actuating means therefor acting when the needle-supporting means and the hammer are relatively in substantially extreme retracted position and adapted to shift said arresting member into engagement with the hammer-helve a distance exceeding the normal operative movement of the latter and thereby move it out of the range of movement of its actuating means.
44. In a straightening machine, the combination with needle-supporting means, of an anvil disposed at one side of the needle, a reciprocating hammer moving in a path adjacent said anvil, means for producing between the needle and the hammer relative feeding movements lengthwise of the needle, actuating means for said hammer, adjusting means actuated by the deflection of the needle whereby the stroke of the hammer is varied, and arresting means for interrupting the action of the hammer when the needle-supporting means and the hammer are relatively in substantially extreme retracted position.
45. In a straightening machine, the combination with a support, a rotary chuck mounted thereon and provided with means for rotating the same, a needle-hopper movable toward and from said chuck while in retracted position and during the interrup-
- tion of its rotations, an anvil disposed eccentrically to the axis of rotation of the chuck, a hammer movable in a path adjacent said anvil, hammer-actuating means, hammer-arresting means, a cam-shaft, actuating cams thereon adapted respectively for producing periodically relative feeding movements between said support and the hammer lengthwise of the needle, opening and closing movements to the chuck, and operative movements to said needle-hopper, and for actuating the hammer arresting means for interruption of the action of the hammer after the completion of a feeding movement, and means for arresting the rotation of said chuck during the opening and closing of the same.
46. In a straightening machine, the combination with a traveling carriage, a rotary chuck mounted thereon and provided with means for rotating the same, a needle-hopper movable toward and from said chuck while in retracted position and during the interruption of its rotations, an anvil disposed eccentrically to the axis of rotation of the chuck, a hammer movable in a path adjacent said anvil, hammer-actuating means, hammer-arresting means, a cam-shaft, actuating cams thereon adapted respectively for imparting periodically traveling movements to the chuck carriage, opening and closing movements to the chuck while the carriage remains in retracted position, and operative movements to said needle-hopper, and for actuating the hammer-arresting means for interruption of the action of the hammer in the retracted position of said carriage, and means actuated independently of said cam-shaft for arresting the rotation of said chuck during the opening and closing of the same.
47. In a straightening machine, the combination with a traveling carriage, a rotary chuck mounted thereon and provided with means for rotating the same, a needle-hopper movable toward and from said chuck while in retracted position and during the interruption of its rotations, an anvil disposed eccentrically to the axis of rotation of the chuck, a hammer movable in a path adjacent said anvil, hammer-actuating means, hammer-arresting means, a cam-shaft, actuating cams thereon adapted respectively for imparting periodically traveling movements to the chuck-carriage, opening and closing movements to the chuck while the carriage remains in retracted position, and operative movements to said needle-hopper, and for actuating the hammer-arresting means for interruption of the action of the hammer in the retracted position of said carriage, and means controlled by the travel of the chuck-carriage for arresting the rotation of said chuck during the opening and closing of the same.
48. In a straightening machine, the com-

- 5 bination with a support, a chuck-spindle journaled therein and carrying a needle-chuck, an anvil disposed eccentrically to the axis of the chuck-spindle, a hammer movable in a path adjacent said anvil, and means for producing between said support and the hammer relative feeding movements lengthwise of said axis, of a pulley adapted for connection with the source of power, 10 a frictional connection between said pulley and the chuck-spindle, and means for locking said chuck-spindle from rotation while the pulley continues to rotate.
49. In a straightening machine, the combination with a traveling carriage, a chuck-spindle journaled therein and carrying a needle-chuck, an anvil disposed eccentrically to the axis of the chuck-spindle, and a hammer movable in a path adjacent said anvil, 15 of a pulley adapted for connection with the source of power, a frictional connection between said pulley and the chuck-spindle, and means including interengaging parts respectively fixed and movable with said carriage for locking said chuck-spindle from rotation while the pulley continues to rotate.
50. In a straightening machine, the combination with a traveling carriage, a chuck-spindle journaled therein and carrying a 20 needle-chuck, an anvil disposed eccentrically to the axis of the chuck-spindle, and a hammer movable in a path adjacent said anvil, of a pulley adapted for connection with the source of power, a frictional connection between said pulley and the chuck-spindle, means for locking said chuck-spindle from rotation while the pulley continues to rotate and including a stud fixed upon the chuck-spindle, a stop-bolt mounted upon 25 the carriage and movable into and out of the path of movement of said stud, shifting means for said stop-bolt also mounted upon the carriage, and a cam-block mounted upon a fixed support and disposed within the path 30 of movement of the stop-bolt shifting means, whereby the stop-bolt is shifted into and out of operative relation with said stud respectively as the carriage approaches and recedes from extreme retracted position.
51. In a straightening machine, the combination with a traveling carriage, a chuck mounted thereon, a needle-hopper movable toward and from said chuck while in one of its extreme positions, an anvil disposed eccentrically to the axis of said chuck, a hammer movable in a path adjacent said anvil, hammer-actuating means, hammer-arresting means, a cam-shaft, actuating cams thereon adapted respectively for imparting periodically traveling movements to the chuck-carriage, opening and closing movements to the chuck while the carriage remains in retracted position, and operative movements to said needle-hopper, and for actuating the 35 hammer-arresting means for interruption of the action of the hammer in the retracted position of the carriage, a main-shaft operatively connected with said cam-shaft and the hammer-actuating means, a pulley adapted for connection with the source of power, and a yielding connection between said pulley and the main-shaft adapted to yield to permit the stoppage of the main-shaft under abnormal load imposed thereon by the driven parts connected therewith.
52. In a straightening machine, the combination with a needle-holder, means whereby needles may be inserted in and discharged from said holder, an anvil disposed eccentrically to the axis of a needle mounted in said holder, a hammer movable in a path adjacent said anvil, means for producing relative feeding movements between said holder and the hammer, and actuating means for the several movable parts, of a needle-tray formed with a series of needle compartments, a receptacle disposed adjacent said needle-holder and provided with a spout directed toward said needle-tray, and means connected with an operative part of the machine for longitudinally shifting the tray the width of one compartment for delivery of each succession of needles of predetermined number.
53. In a straightening machine, the combination with a needle-holder, means whereby needles may be inserted in and discharged from said holder, an anvil disposed eccentrically to the axis of a needle mounted in said holder, a hammer movable in a path adjacent said anvil, means for producing relative feeding movements between said holder and the hammer, and actuating means including a rotary cam-shaft carrying a series of cams for imparting operative movements to the several movable parts, of a needle-tray formed with a series of needle compartments, a traveling platform therefor provided with a series of ratchet-teeth having a pitch corresponding with the width 40 of said needle compartments, a rock-lever, a pawl mounted thereon in operative relation with said ratchet-teeth, a rotary cam member provided with actuating means for said rock-lever, and an operative speed-reducing connection between said cam member and the cam-shaft.
54. In a straightening machine, the combination with needle-supporting means, of a hammer, and an automatically acting impact-regulator therefor having a constant bearing upon and adapted to limit the advance of the hammer toward the needle.
55. In a straightening machine, the combination with needle-supporting means, of a hammer, and an automatically acting impact-regulator therefor having a bearing upon the article being acted upon removed a substantial distance lengthwise of said article from the face of the hammer.

56. In a straightening machine, the combination with needle-supporting means, of a hammer, and an automatically acting impact-regulator therefor separate from the hammer and having a bearing upon the article being acted upon contemporaneous with the delivery of the hammer stroke. 70
57. In a straightening machine, the combination with needle-supporting means, of a hammer, an automatically acting impact-regulator adapted to limit the advance of the hammer toward the needle, and means for supporting the impact-regulator independently of the hammer. 75
58. In a straightening machine, the combination with needle-supporting means, of a hammer, a resilient hammer-holder, mechanism for operating said hammer-holder, and an automatically acting impact-regulator applied to said mechanism. 80
59. In a straightening machine, the combination with needle-supporting means, of a hammer, an automatically acting impact-regulator therefor, and an anvil interposed between said hammer and impact-regulator. 85
60. In a straightening machine, the combination with needle-supporting means, of a hammer, an automatically acting impact-regulator adapted to limit the advance of the hammer toward the needle, and means whereby the needle is fed helically before the hammer. 90
61. In a straightening machine, in combination, needle-supporting means, a hammer, and an impact regulator for the hammer controlled by the needle at the instant of engagement of the hammer therewith to control the effectiveness of said engagement. 95
62. In a straightening machine, in combination, needle-supporting means, a hammer, an impact-regulator adapted to limit the advance of the hammer toward the needle, and a feeler contacting with the needle and controlling said regulator at the instant of impact. 100
63. In a straightening machine, the combination with needle-supporting means and a hammer, of an impact-regulator, a feeler contacting with the needle between the hammer and the needle point, and a connection between said feeler and impact-regulator. 105
64. In a straightening machine, the combination with a needle-support, an anvil spaced therefrom, and a hammer, of an impact-regulator, a feeler disposed upon the opposite side of said anvil from the hammer and contacting with the needle between the hammer and the needle point, and a connection between said feeler and impact regulator. 110
65. In a straightening machine, in combination, an anvil, a hammer, a hammer-support, and means whereby the forward movement of said hammer-support is arrested when the hammer is at a point slightly more removed from the plane of the anvil than the diameter of the article being straightened and whereby the blow of the hammer is delivered by momentum. 115
66. In a straightening machine, in combination, an anvil, a hammer, a hammer-support, a resilient connection between said hammer and hammer-support, and means whereby the forward movement of said hammer-support is arrested when the hammer is about to deliver its blow and whereby said resilient connection permits the hammer-blow to be delivered by momentum. 120
67. In a straightening machine, in combination, an anvil, a hammer, a resilient hammer-holder, and mechanism for dropping the hammer-holder to the point of about delivering the blow, whereby said resilient holder permits the blow to be delivered by momentum. 125
68. In combination, an anvil, means for rotating the needle on its normal axis, a hammer, a hammer-support, and a stop hit by the hammer-support before the impact of the hammer-head. 130
69. In combination, an anvil, means for turning the needle on its normal axis whereby any bend in the blade is gaged by gyration toward the point, a hammer striking such bend backward of the anvil, and means whereby the impact of said hammer is regulated by the amplitude of such gyration forward of the anvil. 135
70. In combination, an anvil, means for turning the needle on its normal axis whereby any bend in the blade is gaged by gyration toward the point, a hammer striking a succession of blows during each rotation, and means whereby the impact of said hammer is regulated by the amplitude and direction of such gyration. 140
71. In a needle-straightening machine, the combination with a plurality of separated supports, of a hammer movable between the same, means for imparting to the needle an endwise feeding movement relative to one of said supports between extreme positions, and automatically acting means for producing a predetermined number of operative movements of the hammer during the feed of each needle. 145
72. In a needle-straightening machine, the combination with a plurality of separated supports, of a hammer movable between the same, means for imparting to the needle a continuous endwise feeding movement relative to one of said supports between extreme positions, and automatically acting means for producing a predetermined number of operative movements of the hammer during the feed of the needle. 150
73. In a needle-straightening machine, the combination with an anvil, of a hammer movable in a path adjacent the same, feeding means for imparting to the needle endwise movements crosswise of said anvil, actuating 155

means for said feeding means, and means acting independently of the needle for interrupting the operation of the hammer while said actuating means continues in operation.

74. In a needle-straightening machine, the combination with an anvil, of a hammer movable in a path adjacent the same, means for imparting to the needle an endwise feeding movement relative to said anvil, and means for imparting to the hammer a series of operative movements of predetermined frequency during the feeding movement of the needle.

75. In a needle-straightening machine, the combination with a reciprocating hammer, and actuating means therefor, of needle-supporting means, and means for producing between the hammer and needle-supporting means relative feeding movements endwise of the needle and crosswise of the path of movement of the hammer and adapted to present for reception of each impact of the hammer a part of the needle at a predetermined position relative to its length.

76. In a needle-straightening machine, the combination with a reciprocating hammer, and actuating means for imparting thereto operative movements of uniform frequency, of needle-supporting means, and means for producing between the hammer and needle-supporting means continuous feeding movements lengthwise of the needle with dwells at predetermined points while the operative movements of the hammer continue.

77. In a needle-straightening machine, the combination with a plurality of separated supports, and automatically acting means for successively positioning thereon for successive straightening operations needles to be straightened, of a hammer movable between said supports, and automatically acting means for producing series of operative movements of the hammer of predetermined number intermediate said positioning operations.

78. In a needle-straightening machine, the combination with a plurality of separated supports, of a hammer movable adjacent one of said supports, automatically acting means for producing series of operative movements of the hammer of predetermined number, and means for feeding across the last-named support the needle to be straightened at a rate of advance in fixed relation with the frequency of the hammer movements and controlled independently of said needle.

79. In a needle-straightening machine, the combination with a plurality of separated supports, of a hammer movable adjacent one of said supports, automatically acting means for producing successive cycles of operative movement of the hammer each of

predetermined number, and automatically controlled means for feeding across the last-named support the needle to be straightened in the same method of advance during each of said cycles.

80. In a needle-straightening machine, the combination with a plurality of separated supports, of a hammer movable adjacent one of said supports, automatically acting means for producing successive cycles of operative movement of the hammer each of predetermined number, and feeding means constructed and adapted to advance a needle to be straightened across the last-named support a distance which is uniform for each of said cycles.

81. In a needle-straightening machine, the combination with an anvil, of a hammer movable in a path adjacent the same, a movable needle-support, feeding means connected therewith for moving it toward and from the path of movement of said hammer, and automatically acting means for imparting to the hammer operative movements each at its predetermined distance from said movable support.

82. In a needle-straightening machine, the combination with an anvil, a traveling needle-support movable toward and from the same, and a hammer movable in a path adjacent said anvil, of automatically acting means for producing series of operative movements of the hammer of predetermined number, and means whereby the needle-support is caused to assume predetermined positions at different distances from the anvil for the initial and final operative movements of said hammer.

83. In a needle-straightening machine, the combination with an anvil, of a hammer movable in a path adjacent the same, a needle-support having a fixed range of movement toward and from said anvil, feeding means connected with said support, and automatically acting means for producing a plurality of operative movements of the hammer of uniform frequency throughout the operative movements of said support toward the anvil.

84. In a straightening machine, the combination with needle-supporting means, of a hammer engaging the needle upon one side thereof, a feeler supported independently of the hammer and contacting with the needle upon the opposite side thereof, and an impact-regulator controlled by the feeler.

In testimony whereof I have signed my name to this specification in the presence of two subscribing witnesses.

WILLIAM TIVENDALE.
